DESIGN FOR A RESPIRATOR

William E. McCormick, Mount Penn, Pa., assignor to Willson Products, Inc., Reading, Pa., a corporation of Pennsylvania

Application October 27, 1941, Serial No. 103,902

Term of patent 14 years

To all whom it may concern:

Be it known that I, William E. McCormick, a citizen of the United States, residing at Mount Penn, in the county of Berks and State of Pennsylvania, have invented a new, original, and ornamental Design for a Respirator, of which the following is a specification, reference being had to the accompanying drawing, forming part thereof.

Fig. 1 is a plan view of a respirator, showing my new design.

Fig. 2 is a side elevational view of the same.

Fig. 3 is a front elevational view of the same.

I claim:

The ornamental design for a respirator, as shown.

WILLIAM E. McCORMICK.
